UNITED STATES PATENT OFFICE.

ELIAS E. WIDDIFIELD AND OLIVE H. WIDDIFIELD, OF TORONTO, ONTARIO, CANADA, ASSIGNORS OF ONE-HALF TO JOHN ROBERT CARTER, OF SAME PLACE.

DESIGN FOR A MAT.

SPECIFICATION forming part of Design No. 14,133, dated July 24, 1883.

Application filed April 27, 1883. Term of patent 14 years.

To all whom it may concern:

Be it known that we, ELIAS EDWARD WIDDIFIELD and OLIVE HULDA WIDDIFIELD, both subjects of the Queen of Great Britain, and 5 now residing in the city of Toronto, in the county of York, in the Province of Ontario, Canada, have jointly invented and produced a new and original Design for Mats, of which the following is a specification, reference being had to the accompanying drawings, forming part thereof.

The design consists of a mat made of sheep or other skin, the wool or hair of the skin forming the center of the mat being clipped, while 15 the wool or hair forming the fringe around the mat being simply combed out, the joint between the fringe skin and the center skin being ornamented by a series of balls.

Figure 1 represents a round mat; Fig. 2, an 20 oval mat, and Fig. 3 a rectangular mat.

A is a skin forming the center of the mat.

B is the fringe of combed wool or hair. The skin to which the fringe is attached is sewed or otherwise fastened around the edge of the center skin A.

C are a series of balls made of clipped unspun wool, and sewed or otherwise attached to the mat at the point where the fringe is attached to the center.

What we claim as our design is—
A mat having a center of clipped wool, and a bordering fringe of combed wool, the joint between the fringe and center being covered or protected by a series of balls made of clipped unspun wool.

E. E. WIDDIFIELD.
O. H. WIDDIFIELD.
